UNITED STATES PATENT OFFICE.

JOHN HAYS HAMMOND, JR., OF GLOUCESTER, MASSACHUSETTS.

SYSTEM AND METHOD OF TELEVISION.

Application filed August 15, 1923. Serial No. 657,502.

This invention relates to systems and methods for the transmission and reception by means of electricity, magnetism or electro-magnetic waves, variations or impulses 5 of pictures, photographs, images, reflections, shadows, patterns or the like, either in black and white or in natural colors. For convenience in nomenclature these systems and methods may be referred to hereinafter 10 systems and methods of television. The energy transmitted from the sending station to the receiving station may be conveyed or guided by wires, or may be transmitted through the other radiantly.

Some of the objects of this invention are to provide an improved system of television; to provide an improved method of television; to provide in a system of television an improved transmitting system and a corresponding receiving system; to provide a system of television including a transmission system and a receiving system controlled thereby through the natural medium as, for instance, by radiant energy; to provide a system and method of television whereby an image of a moving object at the transmitting station may be produced at the receiving station in the form of a moving picture; to provide a system and method of television whereby an image of an object at the transmitting station may be produced at the receiving station in the natural colors of the object; to provide a system and method of television whereby a plurality of overlapping images of an object, as viewed from different points at the transmitting station may be produced at the receiving station in the natural colors of the object, and may be viewed by an observer at the receiving 40 station to produce a stereoptic image of the object in the natural colors of the object; and to provide other improvements, as will appear hereafter.

In the accompanying drawings all of the 45 figures are diagrammatic representations of systems or parts of systems constructed in accordance with this invention or are diagrams explanatory of the operation thereof.

Figure 1 shows a sending station; Fig. 2 50 a receiving station arranged to co-operate with the sending station of Fig. 1; Fig. 3 a modified wave form emitted by the sending station of Fig. 1; Fig. 4 a path of a beam of light during the operation of the 55 sending station of Fig. 1; Fig. 5 a modified

form of operation of the sending station of Fig. 1, arranged to control the path of the beam of light in a manner different from that of Fig. 1; Fig. 6 the wave form emitted by the modified transmitter shown in Fig. 60 5; Fig. 7 the path of the beam of light during operation of the system of Fig. 5; Fig. 8 a modified form of operation of the sending station of Fig. 1 arranged to control the path of the beam of 65 light by rotating mirrors or the like; Fig. 9 the path of the beam of light in operation of the modified form shown in Fig. 8; Fig. 10 a modified form of the sending station of Fig. 1 arranged to limit the 70 amount of light effective to control the emitted energy; Fig. 11 another modified form of the sending station arranged to control the emitted energy according to the light reflected from the parts of the image successively; Fig. 12 a modified form of receiving apparatus employing cathode rays; Fig. 13 a modified form of sending station for use in transmitting pictures in colors and for reproducing stereoscopic images; Fig. 14 an enlarged front elevation of a detail of Fig. 13; Fig. 15^A is a modification of Fig. 13; Fig. 15^B a receiving station arranged to co-operate with either the sending station of Fig. 13 or 15^A; Figs. 16 and 17 75 represent respectively a radio transmitting system and a corresponding radio receiving system which may be substituted for the wire connections between the transmitting system of Fig. 1 and the receiving system 80 of Fig. 2; Fig. 18 shows a modification of the transmitting system of Fig. 1; Fig. 19 a front elevation of a detail of Fig. 18; Fig. 20 a diagram partly broken away of a modified form of light producing and varying 85 system; and Fig. 21 a diagram of a system for increasing the visibility of an object.

Referring to the accompanying drawings, and particularly to Figure 1, one embodiment of this invention comprises a light producing system 10 for producing a beam of light; a vibrating system 11 for causing the beam of light produced by the system 10 to travel in certain predetermined paths; an electric generating system 12 for producing 100 suitable electrical harmonics to operate the vibrating system 11; a photo electric system 13 for receiving the light reflected from an object 14; an electrical amplifying system 15 controlled by the photo electric sys- 105 110

tem 13; and a carrier wave generating system 16 arranged to be controlled by the amplifying system 15.

The light producing system 10 consists of a suitable source of light such as a projector lamp 20 which receives its current from a local battery 21. The light from the lamp 20 and also that reflected from a concave mirror 22 passes through a suitable optical system such as a series of lenses 23, 24 which concentrate the beam of light and project it as a parallel beam 25. The central portion of this beam passes through a small opening in a diaphragm 26 thus producing a very small pencil or beam of intense light 27.

The vibrating system 11 consists of two small mirrors 30 and 31 mounted for rotation in a vertical and horizontal axis respectively. These mirrors are secured to the 20 vibrating elements of suitable galvanometers, the coils of which are shown at 32 and 33 respectively. The coils 32 and 33 oscillate between poles of permanent magnets 34 and 35. The current to the coil 32 is lead in by suitable conductors 40 and 41 which are connected to terminals 42 and 43. The current to the coil 33 is lead in by conductors 44 and 45 which are connected to terminals 46 and 47. The mirrors 30 and 31 and all 25 hereinafter mentioned mirrors are very small in area and very light in weight and are preferably made of very thin sheet metal having one side highly polished to form an efficient reflecting surface. These mirrors 30 may be circular in outline or of any other suitable shape.

The beam of light 27 is reflected from the mirror 30 to the mirror 31 and thence on to the object 14 a picture or image of which is 30 to be transmitted to the distant receiving station.

The electric generating system 12 consists of a high frequency alternator 50 of approximately 3200 cycles per second. The field 45 51 of this alternator is energized from a low frequency alternator 52 of about 16 cycles per second. The alternator 50 is connected by means of transformer 54 to a circuit 55 which is connected to the terminals 42, 43, 50 46 and 47 and also to conductors 56 and 57 which are in turn connected to a filter 58. This filter 58 is constructed and arranged to let pass only currents having frequencies within the band of frequencies produced in 55 the circuit 55 of the alternator 50 as acted upon by the alternator 52. This filter 58 prevents short circuiting of the amplifier 15 and generator 16 through the circuit of the vibrating system 11. This filter 58 and all 60 other filters hereinafter described should be aperiodic with no difference of time lag for different frequencies.

The photo electric system 13 comprises a lens system 60, 61, a photo-electric cell 62 of 65 any suitable construction, and a battery 63

in circuit in series with the cell 62. The light received by the object 14 due to the action of the beam 27 and reflected by the object 14 upon the lens system 60, 61, is focused on the photo-electric cell 62 and varies the 70 amount of current flowing through the cell from the battery 63 accordingly, depending upon the amount and intensity of the light received by the cell.

The electrical amplifying system 15 for 75 amplifying the current produced by the photo-electric system 13 may be of any suitable construction, and in the form shown is of the multiple stage resistance coupled type employing several three element thermionic 80 amplifiers 64. The output circuit of this amplifier 15 is connected to the central terminals of a double pole, double throw switch 65 one side of which is connected to the carrier wave generating system 16 and the 85 other side of which is connected to the input side of an electrical filter 66. This filter 66 is constructed and arranged to let pass only currents having frequencies within the band of frequencies produced by the amplifying 90 system 15 under the control of the photo-electric cell 62 while acted upon by the light received from the object 14 through the lens system 13.

The carrier wave generating system 16 95 may be of any suitable type and in the form shown employs a three element thermionic oscillator 67, and a three terminal thermionic modulator 68 controlled thereby and which is provided with an output circuit 100 leading into the input side of a suitable filter 69. The filter 69 is constructed and arranged to let pass only currents having frequencies within the band of frequencies produced by the carrier wave generating system 105 105 as modulated by the output of the amplifier system 15 under the control of the photo-electric cell 62.

The output sides of the filters 66 and 69 are connected respectively to the two opposite sides of a double pole, double throw switch 70, the central terminals of which are connected to the transmission line 71 by means of conductors 72 and 73. The transmission line 71 consists of two conductors 115 74 and 75 which are connected at their inner ends to the output side of the filter 58, and at their outer ends to a suitable receiver such for instance as is shown in Fig. 2, either directly as for wire transmission, or indirectly as through suitable radio transmitting and receiving apparatus, as shown for instance in Figs. 16 and 17.

Referring to Fig. 2, one form of receiving apparatus which may be employed to 125 cooperate with the form of transmitter shown in Fig. 1, comprises an amplifier detector system 81 for receiving, detecting and amplifying the modulated current from the transmitter; an amplifying system 82 for 130

receiving and amplifying the unmodulated current from the transmitter; a light producing system 83; a light varying system 84, a vibrating system 85; and a suitable screen 86 for receiving the images sent from the transmitter.

At the receiving station the transmission line 71 from the sending station is connected by conductors 90 and 91 to the centre of a double pole, double throw switch 92, one side of which is connected to a filter 93 and the other side of which is connected to another filter 94. The filter 93 is constructed and arranged to let pass only currents of frequencies which are permitted to pass through the filter 69 of Fig. 1 and the filter 94 is constructed and arranged to let pass only currents of frequencies which are permitted to pass through the filter 66 of Fig. 1. The output side of the filter 93 is connected to the input side of the amplifier detector system 81, and the output side of the filter 94 is connected to the input side of the amplifying system 82. The output side of the amplifier detector system 81 is connected to one side of a double pole double throw switch 95, and the output side of the amplifying system 82 is connected to the other side of the same switch 95. The amplifier detector system 81 may be of any well known or suitable construction, and as shown comprises several three element thermionic bulbs 96 of well known construction, resistance coupled and arranged in series. The first bulb 96 on the left is adjusted to act as a detector and also as an amplifier and the next two bulbs 96, 96 are adjusted to act as amplifiers of the current which results from the detection by the first bulb. The amplifying system 82 may be of any well known or suitable construction and in the form shown is of the multiple stage resistance coupled type employing three element thermionic amplifiers 97.

The light producing system 83 is essentially similar to that shown in Fig. 1 at 10, and consists of a source of illumination 100, a lens system 101, 101 and a diaphragm 102, which produces a pencil of intense light 103.

The light varying system 84 comprises a Nicol prism 105, a polarization cell 106, a Nicol prism 107 and a lens system 108. The polarization cell 106 is surrounded by a coil 109 which is connected by conductors 110 and 111 to the central terminals respectively of the switch 95. These parts are so arranged that the pencil of intense light 103 passes from this diaphragm 102 through the Nicol prism 105 and then through the polarization cell 106. The light beam 103 after emerging from the polarization cell 106 passes through the second Nicol prism 107 which is crossed with respect to the first Nicol prism 105. The lens system 108 is

provided for concentrating the beam 103 in case the same has been somewhat diffused in passing through the prisms and polarization cell.

The light vibrating system 85 comprises two mirrors 115 and 116. These are mounted respectively upon the movable elements or coils of two suitable galvanometers comprising respectively permanent magnets 117 and 118, the first mirror 115 is mounted for rotation about a vertical axis so as to receive the beam of light 103 from the lenses 108, and the second mirror 116 is mounted for rotation about a horizontal axis so as to receive the beam of light as reflected from the first mirror 115 and to reflect the same against a suitable screen 86 provided therefor. The vibrating system 85 is similar to that shown at 11 in Figure 1. The current is led into the movable element of the galvanometer 117 by means of conductors 120 and 121 which are connected respectively to terminals 122 and 123, and the current is led into the movable element of galvanometer 118 by means of conductors 125 and 126 which are connected respectively to terminals 127 and 128. The conductor 74 of the transmission line 71 is connected to the terminal 127 and the conductor 75 is connected to the terminal 123. The terminals 122 and 128 are connected together by a conductor 130. A filter 131, similar to filter 58, is inserted in the transmission line 71 and is arranged to let pass only currents of frequencies passed by filter 58.

In the form of the invention shown in Figures 1 and 2, the frequency of the alternator 50 is approximately 3200 cycles per second, and the amplitude of the current generated will depend upon the intensity of the field 51.

In Fig. 1 the vibrating element 32 is tuned so that its natural period is above that of the current produced by the alternator 50 and this vibrating element is thereby caused to vibrate 45 degrees out of phase with the current; and the vibrating element 33 is tuned so that its natural period is below that of the current produced by alternator 50 and this vibrating element 33 is thereby caused to vibrate 45 degrees out of phase with the current in the other direction, with the result that the two mirrors 30 and 31 will vibrate at the frequency of the alternator 50 but with a 90 degree phase relation to each other.

When the beam of light 27 is reflected from the mirror 30 it will be given a vibratory motion in a horizontal plane and when it is reflected from the mirror 31 there will be a vibratory motion in a vertical plane superimposed upon the former vibration. If the amplitude of the current produced by the generator 50 were constant the amplitude of vibration of the two mirrors 30 and

31 would also be constant and the beam of light 27 as it leaves the mirror 31 would have a circular motion. But the field 51 of the alternator 50 is energized by the second 5 alternator 52 so that the amplitude of the current produced by the alternator 50 is varied in a manner shown in Figure 3, where the curve of this current is indicated by the line 135 and the envelope of these curves 10 by the line 136. This will cause the amplitude of vibration of the mirrors to vary so that the beam of light 27 when it leaves the mirror 31 will describe a spiral path as shown in Figure 4. This spiral will always 15 be made in the same direction, for example, as indicated by the arrows in Figure 4, and will start from a central point moving outward in a left hand spiral and will return to the central point over a similar right hand 20 spiral. This spiral will not be reentrant but will always be formed by the point of light moving over the object with the same direction of rotation.

As the frequency of vibration of the mirrors 25 30 and 31 is constant the rate of rotation of the point of light forming the spiral will also be constant and in order to have the intensity of illumination of the object uniform the spacing of the spiral must decrease at a rate proportional to the increase 30 of radius, as the linear speed of the point of light increases directly as the radius. This can be accomplished by making the wave 35 form of the current produced by the generator 50 and shown by the current line 135 (Fig. 3) of such a shape that its envelope 136 will have a parabolic form.

The point of light traversing the spiral path will pass consecutively over substantially every point of an object whose dimensions do not exceed those of the limits of the spiral, the time taken in passing over each complete spiral out and back being 1/16 of a second when the speed of the alternator 52 45 is sixteen cycles per second.

The light reflected from each point of the object as the point of light strikes it will be focused by the lens system 13 on the photo electric cell 62, thereby varying the resistance 50 of this cell accordingly thus producing corresponding variations in the current supplied by the battery 63 to the amplifying system 15 which, depending upon the position of the switches 65 and 70, either sends 55 these amplified variations of current through the filter 66 to the line 71, or else causes them to modulate the high frequency waves produced by the carrier wave generating system 16 which are then sent through the filter 69 60 to the line 71. The alternating current produced by the generating system 12 passes through the filter 58 and then on to the line 71.

In the operation of the sending station 65 shown in Fig. 1 in cooperation with the

receiving station shown in Fig. 2 when it is desired to transmit only the current output of the amplifier system 15 of Fig. 1, then the switches 65 and 70 of Fig. 1, and 92 of Fig. 2 should be so set as to put in series the 70 amplifier system 15, and filter 66 of Fig. 51, line wire 71 and filter 94, amplifier system 82, and coil 109 of Fig. 2.

But if it should be desired to transmit from the sending station the comparatively 75 high frequency current generated by the carrier wave producing system 16 and modulated by the output current of the amplifier system 15, then the switches 65 and 70 of Fig. 1 and 92 of Fig. 2 should be so set as to place in series the amplifier system 15, the carrier wave generator 16, and the filter 69 of Fig. 1, the line wire 71, and the filter 93, amplifier detector system 81, and coil 109 of Fig. 2.

When it is desired to transmit energy by wire from the sending station of Fig. 1 to the receiving station of Fig. 2 either of the sets of connections just described may be made.

After the current has been received and amplified by either system 81 or 82 of the receiving station, as the case may be, it passes to the switch 95 and thence by means of conductors 110 and 111 to the coil 109, which acts upon the polarization cell 106 90 so as to cause a rotation of the plane of polarization through an angle depending upon the intensity of the current in the coil 109. This in turn causes a variation of the amount of light passed through the second 100 Nicol prism 107, so that the intensity of the beam 103 after it leaves the prism 107 will be proportional to the intensity of the light received by the photo electrical cell 62.

The beam of light 103 is then reflected by 105 the vibrating mirrors 115 and 116 which are caused to vibrate in synchronism with the mirrors 30 and 31 at the transmitter, as the coils of the galvanometers 117 and 118 are traversed by the same alternating current 110 which traverses the coils 32 and 33 at the transmitter and which is conducted to the receiver over the conductors 74 and 75. This will cause the point of light produced by the beam 103 on the screen 86 to move over 115 a spiral path similar to that traversed by the beam of light 27 on the object 14.

As the two beams of light 27 and 103 thus move in synchronism and as the beam of light 103 has an intensity proportional to 120 the light reflected from the object 14, at any given instant, the screen 86 will be covered by a point of light making a complete spiral 16 times per second, whose intensity at each point will be the intensity of the light reflected from the object 14 at a corresponding point so that there will be produced on the screen 86 an image which will correspond to the object 14 and which will be produced 16 times per second so that the 125 130

persistency of vision will cause it to appear as a continuous image depicting the object 14 and which will follow closely all the movements of this object.

- 5 In Figure 5 is shown a modified form of the means shown in Fig. 1 for causing the mirrors 30 and 31 to vibrate. In this form of the invention a battery 140 is placed in the circuit with the field 51 and the generator 52. A condenser 141 may also be necessary, forming with the adjacent coil a tuned circuit to take up the irregularities of the 3200 cycle. The wave form of the current generated under these conditions is 15 shown by the line 145 in Figure 6. The envelope of this wave form is shown by the line 146 which is parabolic in shape. With this type of current the pattern formed by the beam of light 27 on the object 14 will be 20 a re-entrant spiral as shown in Figure 7. The spiral will be first formed in one direction as indicated by the arrows 147 and then will retrace this path as indicated by the arrows 148. A similar spiral will be 25 formed on the screen 86 by the beam of light 103 as the coils of the galvanometers 117 and 118 will be traversed by the same current that passes through the coils of the galvanometers at the transmitter. 30 Another form of this invention is shown in Figure 8 in which the pattern is produced by rotating mirrors or similar means instead of by vibrating elements. In this form of the invention the optical system 10 is identical with that described for Figure 1 but in this case the beam 27 is reflected from a plurality of small mirrors 151 secured to the circumference of a circular disk 152 which is mounted upon a shaft 153 which is rotated by an induction motor 154. Secured to the shaft 153 is a worm 155 which meshes with a worm gear 156 which in turn is mounted upon a shaft 157. Secured to the shaft 157 is a second worm 158, meshing 45 with a worm wheel 159 secured to a shaft 160 which carries a plurality of mirror surfaces 161, which reflect the beam of light 27 received from the mirrors 151 to the object 14. When the motor 154 is rotated at a high 50 speed the beam of light 27 will be reflected from each of the small mirrors 151 and each time a mirror passes in front of the incident beam the reflected beam will be rotated through a small angle. This beam is then 55 reflected from the surface of the mirrors 161 which are rotated at a much slower speed than the mirrors 151 due to the worm reduction used. As each vibrating beam strikes the mirror 161 it will be reflected at 60 an angle slightly different from the previous one due to the rotation of these mirrors, thus producing a pattern similar to that shown in Figure 9.
- The induction motor 154 is connected by 65 three conductors 165, 166 and 167 to a similar induction motor 170 located at the receiver. This motor drives a disk 171 provided with a plurality of small mirrors 172, similar to the disk 152, which in turn, by means of a worm reduction gearing, drives the mirrors 175 at a slower rate of speed.
- The optical system at the receiving end is similar to that shown in Figure 2 and the beam of light 103 is reflected first from the mirrors 172 and then from the mirrors 175 to the screen 86. The two induction motors 154 and 170 are supplied from a suitable source of three phase current 180 which drives the two induction motors at the same speed. The two rotating discs 152 and 171 are thereby rotated in synchronism, as are also the mirrors 161 and 175. The pattern formed on the screen 86 is therefore similar to the pattern formed on the object 14, and the beam of light in each case moves over the two patterns synchronously.
- The light reflected from the object 14 of Fig. 8 may be received or picked up by a sending system exactly the same in construction and operation as that part of the 90 sending station shown in Fig. 1, which receives the light reflected from the object 14 of Fig. 1, and which includes the lens system 13, cell 62, amplifier system 15, carrier wave generator 16, filters 66, 69, and line 95 wire 71. This part of the sending apparatus of Fig. 1 forms an unshown part of the sending apparatus of Fig. 8 and the energy transmitted from this unshown part of Fig. 8 may be received upon a receiving system, 100 the same in construction and operation as that portion of the receiving system of Fig. 2 which controls the coil 109 of Fig. 2, to control the coil 109 of Fig. 8. The image produced on the screen 86 of Fig. 8 will 105 therefore be an image of the object 14 of Fig. 8.
- In order to keep the two motors 154 and 170 in practically absolute synchronism, these motors should be of the induction 110 motor type in order to avoid the hunting characteristic of other types. Any suitable means for synchronizing these motors may be employed.
- In the form of the invention shown in 115 Figure 1 the light received by the photo electric cell 62 is comparable to the total illumination of the object at any given instant. As long as the beam of light 27 strikes a part of the surface approximately 120 normal to its direction, as in the case of a photograph or other flat object, the light reflected will be only that amount which is reflected directly from the point where the beam strikes the object. If, however, the 125 image of an object which is not flat but which has depressions and other irregularities of surface is to be transmitted, and the beam should strike the object on a slanting portion of the surface thereof, part of the 130

light will be reflected to other portions of the surface thereof so that the total illumination received by the cell 62 would be not only that reflected directly from the point 5 where the beam 27 strikes the object, but also that reflected from those other portions, thus increasing the illumination received by the cell over that which would be received if only the light reflected directly from the incident point reached the cell. Therefore the system shown in Fig. 1 might operate more efficiently in transmitting images of objects having flat surfaces than in transmitting images of objects having irregular surfaces. 10

To overcome this difficulty and thereby increase the efficiency of the system shown in Fig. 1 when used to transmit images of objects having irregular surfaces, the system shown in Fig. 1 may be modified as shown in Fig. 10 to provide means for causing only the light reflected from the point where the beam 27 strikes the object to be thrown upon the photo-electric cell 62. In this modified form the construction and arrangement are the same as in Fig. 1 except that two secondary mirrors 190 and 191 are added and mounted respectively upon the vibrating elements of the galvanometers 33 and 32 of Fig. 1 so that as these elements vibrate, 20 these secondary mirrors will vibrate in unison with the hereinbefore described primary mirrors 31 and 30. These secondary mirrors 190 and 191 must each be of very small area, and they are mounted at such angles 25 and in such position with respect to the primary mirrors 31 and 30 respectively, that the light reflected by the secondary mirrors will, always be from the point at which the incident beam 27 strikes the object 14 and 30 will always strike the cell 62, which may be rearranged in a new fixed position for this purpose, if necessary. In this modified form of Fig. 1 the lens system 60, 61 may be omitted. 35

Figure 11 shows another modification of Fig. 1, which may be found to have certain advantages for certain purposes. In this modified form of sending station the construction and arrangement may be exactly 40 the same as in Fig. 1 except that the system 10 of Fig. 1 for producing the beam of light 27 is omitted; a lamp 200 and suitable reflectors 201 are arranged to illuminate the object 14; and the cell 62 of Fig. 1 is arranged in Fig. 11 to receive light rays 202 reflected to it by the vibrating system 11 from the object 14. In Fig. 1 the light proceeds from the lamp 20 to the vibrating system 11 and is reflected by the vibrating system 11 to the object 14 and by the object 14 to the cell 62, but in Fig. 11 the light proceeds from the lamp 200 to object 14 and is reflected by the object 14 to the vibrating system 11 which reflects the same to the cell 62, the process of operation of the re-

flecting system in Fig. 11 thus being the reverse of the process in Fig. 1. The vibratory mirrors should be very small in area and very light in weight in all the herein described systems, and this is particularly important in the systems of Figs. 10 and 11. 70

Instead of producing the image by ordinary light rays thrown upon an ordinary screen as in Fig. 2, it is possible to modify Fig. 2 so that the image may be produced 75 on a fluorescent screen by means of cathode rays. In this modification the construction and arrangement are the same as in Fig. 2 except that instead of the means 83 for producing a beam of light, the light modifying 80 system 84 including the coil 109 and connections 110, 111 the vibrating system 85 and the screen 86, of Fig. 2, there is substituted the construction and arrangement shown in Fig. 12. 85

In Fig. 12 is shown an elongated highly evacuated glass bulb or container 205 which is substantially circular in transverse section throughout its length and which comprises a cylindrical neck portion and a substantially cylindrical body portion, the body portion being of greater diameter than the neck portion. Within the outer end of the neck of the bulb is located a cathode in the form of a filament 206, and in the outer end of the body of the bulb and in a plane perpendicular to the longitudinal axis of the bulb is located a fluorescent screen 207. The filament 206 is heated by a battery 208 working through a variable resistance 209. Within the neck of the bulb 205 and between the filament 206 and the screen 207 are located in the order named 90 an anode 210, a focusing gride 211 and a secondary diaphragm 212. 95

The anode 210 is in the form of a circular diaphragm provided with a marginal cylindrical tubular extension 215 and with a central cylindrical tubular extension 216 open at both ends. These two extensions are arranged coaxially with the bulb 205 and the central extension 216 is open at both ends to permit electrons from the filament 206 to pass through the anode 210. The anode 210 is connected to the circuit of the filament 110 206 through a battery 220 of relatively high voltage, for instance of a voltage of from 200 to 1000 volts. 115

The focusing grid 211 is in the form of an elongated coil having its longitudinal axis 120 coincident with the longitudinal axis of the bulb 205. One end of this grid is connected through a condenser 225 with one of the central terminals of the switch 95 of Fig. 2, and the other central terminal of the switch 95 is connected through a battery 226 with the anode 210 of Fig. 12. The opposite sides of the condenser 225 are connected by high resistances 227, 227 with the connection between the switch 95 and the battery 226. 125 130

The diaphragm 212 is flat and is circular in outline provided with a central opening 230. Located outside of and adjacent to the tube 205 and just to the right of the 5 diaphragm 212 are two coils 231 and 235 which have their axes perpendicular to each other and to the longitudinal axis of the tube 205. The ends of these coils 231 and 235 are electrically connected respectively 10 to the corresponding terminals 122 and 123 and 127 and 128 of Fig. 2.

In the operation of the sending system shown in Fig. 1 in connection with the receiving system shown in Fig. 2 modified as 15 shown in Fig. 12, the operation of the sending system and the unmodified portion of the receiving system is as hereinbefore described to deliver energy to the switch 95 of Figs. 2 and 12 and through this switch the 20 energy acts upon the circuit of the focusing grid 211 of Fig. 12 to vary the voltage of the grid in accordance with the variations in the received energy.

The filament 206 of Fig. 12 heated by the 25 battery 208, and under the influence of the high voltage battery 220, causes electrons to be discharged towards the anode 210. Part of these electrons pass through the tubular extension 216 and then through the 30 focusing grid 211 which is normally acted upon by the battery 226, causing these electrons to be to a certain extent diffused so that only a small proportion of them pass through the opening 230 in the diaphragm 35 212. When the intensity of the voltage supplied by the amplifying system to the switch 95 is increased due to the increase of the illumination of the cell 62 of the transmitter, the applied voltage on the grid 211 will be decreased so that the scattering effect will 40 also be decreased and more electrons will pass through the opening in the diaphragm 212 thus increasing the illumination on the fluorescent screen 207. In this way the illumination on this screen will be made proportional to the illumination of the cell 62, and therefore, to the light reflected from the 45 object 14 to the cell 62 at any given instant. As the electrons leave the opening 230 in the diaphragm 212 they will be acted upon by 50 the two coils 231 and 235 which will deflect them an amount depending upon the intensity of the current in these coils at any given instant and as this intensity varies in the same manner as the intensity of the 55 current in the galvanometers at the transmitter the stream of electrons will be caused to describe a spiral path upon the fluorescent screen 207 which will be similar to the spiral path produced upon the object 14 at the 60 transmitter so that an image of the object 14 will be produced on the screen 207.

For transmitting in natural colors the image of an object and for producing an image having a stereoscopic effect and in 65 the natural colors of the object this inven-

tion may be modified for example as shown in Figs. 13, 14, 15^A and 15^B.

In Figs. 13 and 14 is shown one form of transmitter which may be used for the purpose just mentioned. This form of transmitter is in some respects similar to the transmitter shown in Fig. 11 and comprises a source of light 300 arranged to illuminate the object 14, an image of which is to be transmitted; a multiplex light reflecting and 70 vibratory system 305 for receiving light rays reflected from the object 14; a chromatic light disintegrator 310 for receiving and chromatically disintegrating the light rays reflected to it by the reflecting system 75 305; a multiplex photo electric system 315 and an energizing system 316.

The source of illumination 300 may be of any suitable kind, and in Fig. 13 comprises an electric lamp 325 energized by a battery 80 326 and provided with a reflector 327. The reflector 327 is arranged to throw light rays upon the object 14 and to shield the lamp 325 from the light receiving parts 305, 310 85 and 315 of the system.

The multiplex light reflecting and vibratory system 305 comprises two pairs of mirrors 330, 331 and 332, 333, very small and very light in weight secured respectively to two pairs of vibratory coils or elements 335, 90 336 and 337, 338 forming parts of four suitable galvanometers respectively. These vibratory elements 335 to 338 are connected in series in a circuit 339 including a coil 340 arranged to be energized as hereinafter described and arranged to deliver its current through a filter 341 to output conductors 342, 343 and thence to the line as will appear hereinafter. The filter 341 is constructed to let pass only waves of the band 100 of frequencies flowing through the input circuit 339 to vibrate the mirrors 330 to 333. The mirrors 330 and 332 are arranged to be vibrated about fixed vertical axes and the mirrors 331 and 333 are arranged to be vibrated about fixed horizontal axes respectively.

The chromatic light disintegrator 310 comprises a substantially flat circular color separating screen or filter 350 (shown enlarged in Fig. 14). This screen 350 comprises a hub 351 surrounded by a rim 352 concentric therewith and rigidly supported therefrom by a plurality of arms or spokes 353 radiating from the hub 351 to the rim. In the openings between the spokes 353 are secured colored segments 354, 355 of translucent material such for instance as glass, and these segments are in this form of the invention alternately of complementary colors, for instance, one segment 354 of an orange red and the next segment 355 being of a greenish blue, these two colors being well known in color photography, the light 115 of these two colors uniting to produce white 120 125 130

or colorless light. In the screen shown six segments are used and these are of equal size and of the same form and so arranged that a segment of one color is always diametrically opposite to a segment of the complementary color. The screen 350 is arranged to be rotated by an induction motor 360 upon the shaft 361 to which the screen is centrally and rigidly secured, the rotation 10 of the screen 350 being at such a rate and so synchronized with respect to the vibrations of the vibratory system 305 including the mirrors 330, 333, that the screen rotates through an arc of 360 degrees divided by 15 the number of equal colored segments 354, 355, while the vibratory system is making one complete cycle of operations.

The photo-electric system 315 of Fig. 13 comprises two photo-electric cells 365, 366, 20 of any suitable material the electric resistance of which is varied by and in accordance with the action of light rays of varying intensity. These cells are respectively in two circuits 367, 368 which control respectively 25 two electrical current amplifier systems 369, 370, which may each be of the same construction as the amplifier system 15 of Fig. 1. These two amplifier systems 369 and 370 control respectively two systems 371, 372 30 for the production of two series of carrier waves of different frequencies respectively, for instance, of frequencies of 25,000 and 30,000 respectively. Each of these two carrier wave generating systems may be of the 35 same construction as the carrier wave generating system 16 of Fig. 1, each including a three element thermionic oscillator, and a three element thermionic modulator. These two generators 371 and 372 are connected to 40 deliver their outputs to two aperiodic wave filters 373 and 374 respectively, which are constructed to let pass respectively only waves of the two bands of frequencies produced by the generators 371 and 372 re- 45 spectively and have no time lag. These two filters avoid among other things short circuiting of the generators 371, 372, and short circuiting of the current flowing through the filter 341. The output of filters 371, 372 50 are conducted to a line wire 375 comprising two conductors 376, 377, which connect the transmission system of Fig. 13 with a receiving system, for instance, such as is shown in Fig. 15^B. The outer ends of the output 55 wires 342 and 343 of the filter 341 of the transmission system are also connected respectively to these line wires 376, 377.

For electrically energizing the color separating system of the sending station of Fig. 13, and for synchronously energizing corresponding parts of the receiving station as will appear hereinafter, an alternating current generator 400 is provided and arranged to deliver its output to three wires 401, 402, 60 403, which connect the sending station (Fig.

13) with the receiving station (Fig. 15^B). The wires are electrically connected respectively at the sending station to the motor 360 by three wires 405, 406, 407. The armature of the generator 400 is arranged to be 70 rotated at a constant rate by any suitable means, as for instance by a motor 410 receiving its energy from a source not shown.

For vibrating the mirrors 330, 331, 332, 75 333 of light reflecting system 305 of the sending station and synchronously vibrating corresponding mirrors of the receiving station, as will appear hereinafter, the coil 340 of Fig. 13 is arranged to form the secondary coil of a transformer 415 having a primary 80 coil 416 in a circuit 417 receiving energy from an alternating current generator 420, the same in construction and operation as the generator 50 of Fig. 1, except that it produces an alternating current of for instance twice 85 the frequency of the current of the generator 50, or in other words, a current of 6400 cycles per second. An auxiliary alternating current generator 421 corresponding to the generator 52 of Fig. 1 is securely mounted 90 upon an extended part of the armature shaft of the generator 400 so as to be rotated in unison therewith, and is arranged so as to produce an alternating current of for instance twice the frequency of the current of 95 the generator 52 of Fig. 1, or in other words, a current of 32 cycles per second in a circuit 422 including a coil 423 arranged to act inductively upon the field coil of the generator 420 to vary the amplitude of the output current of the generator 420 accordingly at a constant rate and in synchronism with the rotation of the color separating screen 350. For uniform lighting the generator 420 may be caused to produce a current having a wave 100 form indicated by lines 135 of Fig. 3, the envelope of which 136 may be parabolic in form, as described in connection with Fig. 1.

The construction, arrangement and operation of the transmitting system shown in 110 Figs. 13 and 14 are such that when the object 14 receives light from the source 300 a part of the light will be reflected by the object from a given point or spot 425 on the object along the path 426 to the mirror 330, 115 thence to mirror 331, thence along a path 426' and through one of the segments of disc 350 to the corresponding cell 365; and simultaneously another part of the light will be reflected by the object 14 from the same point 120 425 along the path 427 to the mirror 332, thence to mirror 334, and thence along a path 427' and through a segment diametrically opposite to the first and of complementary color and to the corresponding cell 366. The mirrors 330 to 333 are so arranged that the two mirrors 330 and 332 will always receive light simultaneously from the same point 125 425 of the object 14 and this point will be caused to describe a spiral path moving out- 130

ward over a left-hand spiral from a central point and returning to the same point over a right hand spiral as shown in Fig. 4.

To accomplish this, the vibrating element 336 is tuned so that its natural period of frequency of vibration is above that frequency of the current produced by the alternator 420 and this vibrating element 336 is thereby caused to vibrate 45 degrees out 10 of phase with and in advance of the phase of the current, and the vibrating element 335 is tuned so that its natural period of frequency of vibration is below that of the same current and consequently the vibrating element 335 is caused to vibrate 45 degrees out of phase with and behind the phase of the current with the result that the corresponding two mirrors 331 and 330 will be vibrated at the frequency of the alternator 20 420 but with a 90 degree phase relation of vibration between the mirrors. The vibratory elements 338 and 337 are likewise tuned so that their natural periods of frequencies of vibration are respectively above and below 25 the frequency of the alternator 420 and so that consequently the corresponding mirrors 333 and 332 will be vibrated at the frequency of the alternator 420 but with a 90 degree phase relation of vibration between these 30 two mirrors. If the amplitude of oscillation of the current produced by the alternator 420 were constant, the amplitude of vibration of the mirrors would be constant, and the path traversed upon the object 14 by the 35 point 425 from which the light is received by the mirrors 426 and 332 would be a circle; but since the field of the alternator 420 is energized by a second alternator 421, the amplitude of the oscillations produced by 40 the alternator 420 is varied, thus causing the amplitude of vibration of the mirrors to be varied accordingly and causing the point 425, from which light is received by the mirrors 426 and 332, to describe a spiral 45 path extending from a central point outwardly and then returning to the central point, as shown in Fig. 4, and as hereinbefore described. The time consumed in making a complete cycle of operation of the 50 vibrator system 305 to thus cause the point 425 to travel through a complete spiral path out and back as in Fig. 4 would be one thirty-second of a second when the alternator 421 is delivering current at 32 cycles 55 per second, as assumed. Also during each one thirty-second of a second the point 425 from which light is received will be rotated about the central point of the spiral two hundred times, one hundred in proceeding 60 from the central point outwardly and one hundred in returning, if as assumed the alternator 420 is delivering current at the rate of 6400 cycles per second. Consequently, if the extreme diameter of the object 14, an image of which is to be trans-

mitted, is comparatively small, as for instance not more than two inches, and the electrical devices and connections are so adjusted and operated that the extreme diameter of the spiral path of the point 425 70 would slightly exceed that of the object 14 then the pitch of the spiral, or distance between successive convolutions of the spiral would be only about 1/100 of an inch so that if the mirrors 330 and 332 were each 75 substantially circular in shape and of a diameter slightly in excess of 1/100 of an inch every point on the face of the object 14 would be twice covered by the point 425 in its passage out and back over the spiral path. 80 However, it is evident that the extreme diameter of the spiral path, the number of convolutions in the spiral, the distance between successive convolutions, and the time of producing a complete cycle of the 85 spiral, out and back, all may be varied to suit various requirements, as experience may dictate.

Also in the operation of the transmitter shown in Fig. 13 the various motors and alternators are constantly operated, and the object 14 (here assumed to be a picture in colors on a flat plane suitably arranged) is constantly illuminated by the lamp 325, and light is reflected or radiated from the entire 95 surface of the object 14 in various directions. The vibrating mirror systems reflect the light from consecutive parts of a spiral path 425, as hereinbefore described, so as to cover substantially every part of the object cyclically 100 from the central portion of the object outwardly to the marginal portions of the object and then returning to the central portion at a rate, for instance, of 64 cycles per 105 second.

These two portions of this reflected light which travel respectively from the constantly moving point 425 over the constantly changing paths 426 and 427 to the two mirrors 330 and 332 are reflected respectively 110 by the two mirrors 331, 333 through oppositely arranged complementary colored portions of the rotating color disintegrator 350. The screen 350 is so arranged and rotated, and the number of colored segments in the screen is so chosen, that, disregarding the arms 353 of the screen, throughout one entire cycle of vibrations of the mirrors 330—333, the opposite rays 426, 427 will 115 pass through, for instance, a blue green segment and an oppositely arranged orange red segment respectively, and during the whole of the next cycle will pass through an orange red segment and a blue green segment respectively. Consequently, the rays 426' 120 and 427' striking the cells 365 and 366 will be correspondingly colored during one cycle and reversed in color during the next cycle of vibrations of the mirrors and will control the two photoelectric cells 365 and 366 125 130

accordingly to produce corresponding variations in the currents flowing therethrough. These currents are amplified by the amplifiers 369, 370 and these amplified currents 5 correspondingly modulate respectively the two series of carrier waves produced by the two carrier wave generators 371, 372 respectively, and these two series of carrier waves thus modulated pass through the filters 373, 10 374 respectively and over the line 375 to the receiving station.

In Fig. 15^A is shown a modification of the transmitter of Fig. 13. Corresponding parts of this figure are designated by the 15 same reference numerals. In this system a light source 20 with suitable condensing and focusing means 22, 23, 24 and 26 is provided. The amount of light is regulated by the disc 801 driven by motor 804 which is synchronized in its motion with the motion of the 20 mirrors 330, 331, 332 and 333, as will be more fully explained hereafter in connection with Figs. 18 and 19. The light thus produced and regulated is reflected by the mirrors 380 and 381 and to the object 14 by means of the mirrors 330^A, 331^A, 332^A and 25 333^A, to illuminate the object in the same path along which it is being scanned as has been described in connection with Fig. 10.

30 The function of the controlling motor 410 and the amplifying, modulating and filtering devices 315, 316 and 373 respectively etc., is the same as that of the corresponding parts in Fig. 13, which has been described 35 above.

Thus there is produced a system which will give by means of the color disintegrating device 350 and the dual mirror systems an improved stereoscopic transmission in 40 natural colors.

In Fig. 15^B is shown one form of receiving system which may be used in combination with the transmission system shown in Figs. 13, 14 and Fig. 15^A. This receiving system 45 comprises a duplex source of light 500, a color disintegrator 505, a duplex light modulating system 510, a duplex light vibratory system 515, a light receiving and reflecting screen 520, an auxiliary color disintegrator 525, and a duplex electrical receiving system 530.

The duplex source of light 500 comprises two electric lamps 535, 536 of equal intensities and arranged to be energized by a battery 537.

The color disintegrator 505 includes a color separating disc or screen 550, the same in construction as the screen 350 of Fig. 13; and this screen is rotated by a synchronous 60 motor 560 which is arranged to be energized through connections with the three conductors 401, 402, 403 which receive energy from the alternator 400 of Fig. 13. Consequently, the screen 550 of the receiver is synchronized

in its rotation with the screen 350 of the sending station, and the former screen is so constructed and arranged that throughout the cycle when the rays 426' and 427' of the sending station are orange red and blue green respectively, the corresponding rays 568' and 569' of the receiving station will be of the same colors respectively, and when the colors of the rays of the sending station are reversed, the colors of the rays of the receiving station will also be reversed.

The duplex light modulating system 510 comprises a Nicol prism 565, a polarizing cell 566 and an analyzer or second Nicol prism 567 crossed with respect to the first prism 565, all arranged in alignment with the electric lamp 535 to receive and modulate a small beam of light 568 therefrom; and a Nicol prism 570, a polarizing cell 571 and an analyzer, or second Nicol prism 572 crossed with respect to the corresponding first prism 570 are arranged in parallelism with the first mentioned prism 565, cell 566 and prism 567, and in alignment with the other lamp 536 to receive and modulate a second small beam of light 569 therefrom.

The duplex light vibratory system 515 comprises two vibratory mirrors 575, 576 arranged to receive the two small beams of light 568', 569' from the two prisms 567 and 572 respectively, and two vibratory mirrors 577 and 578 arranged to receive light reflected thereto by the two first mentioned mirrors 575, 576 respectively and to reflect the same to a point 579 on the screen 520. These four mirrors 575—578 are arranged to be vibrated respectively by the four vibratory coils or elements 580, 581, 582 and 583 of four corresponding galvanometers. The mirrors 575 and 576 are arranged to be vibrated by the corresponding coils about fixed horizontal axes respectively, the other two mirrors 577 and 578 are arranged to be vibrated by their corresponding coils about fixed vertical axes respectively, and the tuning of the four coils or vibratory elements 580—583 is similar to the tuning of the corresponding coils or vibratory elements 335—338 of Fig. 13, and is such that the four mirrors 575—578 are so vibrated as to cause the point or spot of light 579 to travel over the screen 520 in a spiral path which is a reproduction of the spiral path of movement of the point 425 on the object 14 of Fig. 13. These coils 580—583 are in series in the circuit 376, 377 which receives the alternating current of 6400 cycles per second from the alternator 420 of the sending station modulated at 32 cycles per second by the alternator 421 of the sending station and consequently the mirrors of the receiving station are vibrated in synchronism with the mirrors of the sending station. A filter 585 similar to filter 341 is inserted in the circuit 376,

110
115
120
125

377 and is arranged to let pass only currents of frequencies let pass by filter 341 of Fig. 13.

The auxiliary color disintegrator 525 comprises a color separating disc 600 identical in construction with the hereinbefore described disc 350 of Fig. 13, and arranged to be rotated in synchronism therewith about a fixed axis, perpendicular to the disc 600 and 10 extending through the center thereof and intersecting the central portion of the screen 520, by an induction motor 601 which receives current from the three conductors 401, 402 and 403 leading from the generator 400 15 of Fig. 13.

The duplex electrical receiving system 530 (Fig. 15^B) comprises two band filters 625, 626 and two amplifying systems 630, 631. The filters 625, 626 are connected by two 20 pairs of conductors 627 and 628 respectively to the line 376, 377 from the sending system shown in Fig. 13, and are constructed to let pass respectively only the two series of modulated carrier waves received from the 25 two filters 373 and 374 respectively of the sending system. Two electrical amplifying systems 630 and 631 are connected respectively to the two filters 625, 626 to amplify the outputs of the same and may be of any 30 suitable construction for this purpose. The outputs of these amplifiers are connected respectively to energize two coils 635, 636 which are wound respectively around the two polarizing cells 566, 571. These two coils 35 635, 636 when in operation act to rotate the two planes of polarization of the two polarizing cells 566, 571 respectively in variable degrees depending upon the variations in the received currents due to variations in 40 color and intensity of light emitted or reflected from the constantly moving path 425 on the object 14, an image of which is being transmitted.

In the operation of the receiving system, 45 shown in Fig. 15^B, in connection with the transmission system, shown in Fig. 13, the beam of light 568 from the lamp 535 passes through a colored segment of the screen 550 and through the Nicol prism 565, the polarizing cell 566, and the second Nicol prism 567, being modulated at each stage of its progress and then strikes the vibratory mirror 575 and is reflected thereby to the vibratory mirror 577 from which it is reflected as 50 a constantly moving point or spot 579 on the screen 520; and at the same time that this is occurring, the beam of light 569 from the other lamp 536 passes through a colored segment of the screen 550 diametrically opposed to the first mentioned segment and of a color complementary thereto, and then through the Nicol prism 570, the polarizing cell 571, and the second Nicol prism 572, being correspondingly modulated at each stage of its 55 progress, and then strikes the vibratory mir-

ror 576 and is reflected thereby to the vibratory mirror 578 from which it is reflected to the constantly moving point 579 on the screen 520;

Throughout one cycle of vibrations of the 70 mirrors 575-578, the two beams of light 568' and 569' are always of complementary colors, for instance, of orange red, and blue green respectively, and throughout the next cycle the colors are reversed and this reversal 75 occurs at the point of time when one cycle of vibrations of the mirrors terminates and the next begins.

Therefore, it may be said that the beam of white light 568 sent from the lamp 535 80 is first disintegrated in color by the screen 550 to produce a beam of light which is alternately blue green and orange red in color, or in other words, which is cyclically varied or alternated in color from one color 85 to its complementary color and back again repeatedly at a predetermined rate, the change in color of the beam of light due to the screen 550 taking place in the form shown only between each two successive 90 cycles of vibration of the mirror. But the change in color might be arranged to take place at any other point in the cycle of vibrations of the mirrors without materially effecting the ultimate result. Meanwhile, 95 the other beam of white light 569 is going through a similar process.

At the receiving station, the various operations are all synchronized with respect to the transmitting station, as hereinbefore described, so that the moment that the point 425 on the object 14 of the sending station reflects or emits two beams 426, 427 of white light to the two mirrors 330, 332 respectively, the resistance of the two cells 365, 366 will 100 105 be varied in consequence and in proportion to the intensities of the two beams emitted respectively and will vary or modulate the two carrier waves accordingly, and in consequence at the same moment the current in the two coils 635, 636 of the receiving station will be accordingly varied and consequently the beams of light 568', 569' of complementary colors respectively will be of corresponding intensities and will overlap or 110 115 mingle at the point or spot 579 on the screen 520 of the receiving station to produce the effect of white light. It is also evident that this spot of white light at the receiving station will correspond relatively in intensity 120 at any moment with the combined intensities of the beams 426, 427 being emitted from the spot 425 of the sending station. When the photo-electric cells 365, 366 of the sending station are exposed to light beams 426', 427' 125 respectively the resistance of each cell is decreased in proportion to the intensity of the corresponding beam of light and consequently the greater the intensity of the light in each beam, the greater the electric 130

current flowing through each cell, and the greater the modulation of the two carrier waves transmitted to the receiving station to control the two polarizing cells 566, 571.

5 The arrangement is such that when either coil 635 or 636 receives no current, the corresponding cell will so polarize the light beam received from the corresponding prism 565 or 570 that none of this beam will be permitted 10 to pass through the corresponding second prism or analyzer 567 or 572; but when either coil 635 or 636 receives current the plane of polarization of the corresponding beam of light will be accordingly rotated 15 to a degree dependent upon the amount of current received by the coil to permit a corresponding amount of the beam to pass through the corresponding second prism or analyzer 567 or 572. Thus the intensities 20 of the two beams of light 568', 569' striking the point 579 of the screen 520 at any moment will be proportional to the currents flowing through the coils 635, 636 respectively at that moment and may each vary 25 from zero intensity to full intensity to correspond to the intensities of the light beams reflected at the particular moment from the point 425 on the object 14 to the mirrors 330, 332 respectively of the sending station.

30 If, however, the point 425 on the object 14 of the sending station (Fig. 13) should be during any particular period wholly only of one of the two complementary colors mentioned, either blue green or orange red, 35 it is evident that the beams of light reflected from the point would be only of the same color and after passing through the color screen 350 would be delivered against the two cells 365, 366 in the form of the series 40 of intermittent light impulses of the same color, the impulses of one series striking its cell 365 in alternation with the times that the impulses of the other series strikes its cell 366, and as a result, during the same 45 period the point 579 of the screen 520 of the receiving station would be lighted by two series of intermittent light impulses of the same color, the impulses of one series alternating with the impulses of the other series 50 to give a substantially continuous illumination of the point 579 on the receiving screen 520 in the same color, the intensity of the illumination of the point 579 varying in response to and in accordance with variations 55 in intensity of the light reflected from the point 425 of the object 14 at the sending station.

60 But when the color of the point 580 of the sending station is of a color containing or made up of more or less of the orange red and more or less of the blue green, as components, then the color screen 350 of the sending station will act to separate the two rays 426, 427 into their blue green and 65 orange red components, changing each ray

into a series of successive light impulses alternatively blue green and orange red, each impulse being of a single one of these colors, or components, (either blue green or orange red) throughout the duration of the impulse, 70 but the intensity of the light throughout each impulse may be constant or varied depending upon the intensity of the corresponding color component being reflected or emitted from the point 425 during that impulse, and, as a result, the two rays of colored light 568' and 569' of the receiving station (Fig. 15B) will cooperate at the point 579 either by overlapping or mingling or by alternating to produce at that point an 80 image of the corresponding point 425 of the sending station, in the natural color of the point 425 and of an intensity corresponding to and controlled by the intensities of the light beams emitted from the point 425 to 85 the two cells 365 and 366 respectively. Therefore, since the point 425 at the sending station moves in a continuous spiral from the central part of the object 14 out to or beyond the outermost part of the object and 90 back again respectively and at a predetermined rate (for instance at a rate of 32 times a second) and as the point 579 of the receiving station moves simultaneously in a similar path, as hereinbefore described, there 95 will be produced at the receiving station on the screen an image of the object 14, and in the natural colors of the object, which may be viewed on the screen through the naked eye of an observer.

100 It is evident that this image in colors will be made up of two overlapping images, one produced by the beam 569' and the other produced by the beam 568'.

105 During one cycle of vibrations of the mirrors 575-578, for instance during one period of one thirty second of a second the beam 568' will produce a complete image in one of the complementary colors, for instance in blue green, and during the next one 110 thirty second of a second will produce a complete image of the object in the other complementary color, for instance in orange red, but as the optical effect of the first image remains on the retina of the observer's 115 eye for about one sixteenth of a second after it has actually been cut off of the screen, it has the optical effect of overlapping or mingling with the next succeeding image, so that the total effect is that during two 120 successive cycles of vibrations of the mirrors, for instance during each one sixteenth of a second the beam 568' will produce a complete image of the object 14 in the natural 125 colors of the object as viewed from the point of location of the mirror 330, and during the same one sixteenth of a second the other beam 569' will act in a similar manner and produce on the screen 520 an image of the object 14 in its natural colors as viewed 130

from the point of location of the other mirror 332.

For the purpose of giving a stereoptic effect to the image in colors on the screen 520, this invention provides the auxiliary color disintegrator 525, hereinbefore described. The arrangement shown in Fig. 15^B is such that when an observer stands back of the color disintegrator, he may view the point 579 through a segment of one color with one eye 605 while he is viewing the same point through a segment of complementary color with his other eye 606, and the colored segments of the screen 600 are so arranged that during the cycle when the point 579 is receiving light of one of the complementary colors from the ray 569', a segment of the same color will be in front of the right eye 606 of the observer, and a segment of the complementary color will be before his left eye 605. Consequently, since the screen 600 is synchronized with the screens 350 and 550, the right eye of the observer will see on the screen 520 an image 25 in natural colors of the object 14 of the sending station as viewed from the position of the mirror 332, which may be considered to be in front of and upon the right of the object 14, while the left eye 605 of the observer sees upon the screen 520 an image of the object 14 in natural colors as viewed from the location of the mirror 330, which may be considered to be in front of and upon the left side of the object 14. These 30 two colored images will overlap and produce a stereoptic effect in which the natural colors of the object 14 will be reproduced.

The radio sending system shown in Fig. 16 is designed to produce a high frequency 40 radio carrier wave having a frequency for instance, of 500,000 oscillations per second and modulated in amplitude for instance, at a frequency of 30,000 per second, and also modulated or varied by and in accordance 45 with the light varied current produced in the line 71 by the television system of Fig. 1. This radio transmission system comprises an open aerial circuit 701 provided with a coil 702 and grounded as at 703.

50 For energizing the aerial circuit 701, three thermionic devices 705, 706 and 707, are provided. These may be of well-known or any suitable construction and in the form shown each includes an evacuated bulb 708 containing a filament 709 a grid 710 and a plate 711. The three thermionic devices 705, 706 and 707 are constructed, adjusted and cooperately connected each to each other and all to the open aerial circuit 701, as shown 55 and so that the device 705 acts as a main source of high frequency oscillations forming a carrier wave, of for instance, 500,000 oscillations per second, the device 706 acts as an auxiliary source of oscillations of for 60 instance, 30,000 per second, and the device 65

707 is controlled by the auxiliary oscillator 706, and the line 71 and acts as a modulator of the current produced by the master oscillator 705.

The main or master oscillator 705 is provided with a plate circuit 715 including a coil 716 inductively coupled to the coil 702 of the aerial circuit, a conductor 717, a closed oscillatory circuit 718, a conductor 719, a battery 720 and conductor 725. The 75 closed oscillatory circuit 718 includes a coil 721 and a condenser 722. A battery 723 is provided for heating the filament 709 of the master oscillator 705, the battery being arranged to act through a variable resistance 80 724 and the conductor 725. The master oscillator 705 is also provided with a grid circuit 730 including a condenser 731, a coil 732 and a battery 733. A grid leak 734 is shunted around the condenser 731. For the purpose of regeneration the coil 732 of the grid circuit is inductively coupled to the coil 716 of the plate circuit and also to the coil 702 of the aerial circuit 701.

The auxiliary oscillator 706 is provided 90 with a plate circuit 735 which includes a coil 736, the battery 720, and a conductor 737. The auxiliary oscillator is also provided with a grid circuit comprising a conductor 738 including a coil 739, a battery 95 740, part of a conductor 741 and a variable resistance 742. The filament 709 of the auxiliary oscillator 706 is heated by the battery 723.

For the purpose of regeneration, the plate 100 circuit of the auxiliary oscillator 706 is provided with a shunt connecting the conductor 735 with the conductor 741, and comprising a conductor 743, a condenser 744 a coil 745 and that part of the circuit 735 which leads 105 through the battery 740 and to the conductor 741. The coil 745 of the shunt is inductively coupled to the coil 739 of the grid circuit of the auxiliary oscillator. A coil 752 connecting the outer or right hand ends 110 of the conductors 74 and 75 of Fig. 1 is inductively coupled to the coil 750 of the grid circuit of the modulator 707 and acts to modify the action of the modulator 707 in accordance with the light modified current 115 flowing in the circuit 74, 752, 75.

The modulator 707 is provided with a plate circuit including the plate 711, part of conductor 715, the conductor 717, the closed oscillatory circuit 718, the conductor 719, the 120 battery 720, the conductor 725 and a conductor 746. The filament 709 of the modulator 707 is heated by the battery 723 acting in one direction through the conductor 741, a conductor 747 and a variable resistance 125 748, and acting in the opposite direction through the conductor 725, and the conductor 746. The modulator 707 is also provided with a grid circuit comprising a conductor 749 including a coil 750 and an 130

auxiliary coil 751, the latter being inductively coupled to the coil 745 of the plate circuit 735 of the auxiliary oscillator to modify the action of the modulator in accordance with the oscillations produced in the plate circuit 735 by the auxiliary oscillator 706.

In Fig. 17 is shown a radio receiving system constructed and arranged to receive energy transmitted by the sending system of Figs. 1 and 16 combined as hereinbefore described. This form of receiving system comprises an open aerial circuit 755 including a coil 756 and grounded as at 757. Inductively coupled to the coil 756 is a secondary coil 758 forming part of a closed oscillatory circuit 759 including a variable condenser 760. The aerial circuit 755, 756 and the closed circuit 759 are preferably both tuned to respond to the modulated carrier wave of the sending system.

The closed circuit 759 is arranged to control a primary three element thermionic detector 761 which is of well known or suitable construction and provided with a plate or controlled circuit 762 including a coil 763, a closed oscillatory circuit 764 and a battery 765. A battery 766 is arranged to heat the filament of the primary detector 764.

30 The closed oscillatory circuit 764 includes a variable condenser 767 and a coil 768. The latter is inductively coupled to a coil 769 which forms part of a closed oscillatory circuit 770 including a variable condenser 771. 35 These two closed circuits 764 and 770 are preferably tuned to the frequency of the auxiliary oscillator 706 of the transmitter (shown in Fig. 16) for instance, to a frequency of 30,000 per second. The closed circuit 770 is arranged to control a secondary three element thermionic detector 775 the filament of which is arranged to be heated by the battery 766, and which is provided with a plate or output circuit 776 including 45 a coil 777, which is inductively coupled to a coil 778 provided therefor and connecting the left hand or inner ends of the conductors 74 and 75 of the receiving system shown in Fig. 2.

50 The operation of the radio television system including the transmitting system shown in Fig. 1 in combination with Fig. 16 and the receiving system shown in Fig. 2 in combination with Fig. 17 is as to Figs. 55 1 and 2 the same as heretofore described in connection with Figs. 1 and 2 but instead of sending by wire from the sending station of Fig. 1 to the receiving station of Fig. 2, the electric currents produced in the conductors 60 74 and 75 of Fig. 1, these currents are caused to act through the coil 752 and modulator 707 of Fig. 16 to modulate accordingly the high frequency carrier wave having a frequency of, for instance 500,000 per second 65 which is produced by the master oscillator

705 and modulated at a frequency of for instance 30,000 per second by the auxiliary oscillator 706 acting through the modulator 707. This modulated carrier wave acts upon the aerial circuit 701 of Fig. 1 to cause the emission thereby of corresponding radiant waves which are received by the aerial 755, 756 of Fig. 17 and act to produce in the output coil 768 a current of uni-directional impulses having a frequency of for instance, 75 30,000 impulses per second modulated by and in accordance with the light varied currents in the input coil 752 and these impulses act through the receiving system shown in Fig. 2 to produce as hereinbefore described upon the screen 86 an image of the object 14 of the transmitting station of Fig. 1.

In Figs. 18 and 19 is shown a system which is a modification of the form of the invention shown in Figs. 1 and 2. If, as hereinbefore described, the spacing of the spiral shown in Fig. 4 is uniform, the intensity of the illumination will decrease as the radius of the moving point of light increases, thus making the illumination much brighter at the centre than at the outer portions of the spiral. In order to overcome this difficulty and to produce a uniform illumination, Fig. 1 may be modified by inserting a disc 801 between the hereinbefore described lenses 23 and 24, as shown in Figs. 18 and 19. This disc may be made of glass, or other suitable transparent material, and has part of its surface covered with an opaque substance 802, as shown in Fig. 19. This disc 801 is fixed on the shaft 803 of a synchronous motor 804, which is rotated by alternating current supplied by a generator 805 mounted on the same shaft as the generator 52, so that the disc 801 will be rotated in synchronism with the pulsations of the current in the field 51 of the generator 50. The transparent portion 806 of the disc 801 is so proportioned that when the beam 27 is at the centre of the spiral, the light from the lens 23 will be passing through the narrow portion 807 of the transparent part of the disc 806. As the point of light moves out on the spiral, the disc 801 will be rotated so that at any given instant the amount of light passing through the translucent sector will be proportional to the amount of light required at the given radius of the spiral to produce a constant illumination. In this way the point of light due to the beam 27 as it moves out on the spiral will be changed in intensity so that the resulting illumination of the field will be substantially uniform throughout.

In Fig. 20 is shown a light producing and varying system which may be substituted in Fig. 2 for the light producing system 83 and the light varying system 84 and also may be substituted for each of the light producing and light varying systems 100-107 of 130

Fig. 8, 206—216 of Fig. 12 and 500—510 of Fig. 15.

This system shown in Fig. 20 comprises an evacuated glass tube or bulb 825 preferably containing a gas or vapor such for instance as mercury vapor at relatively low pressure. The bulb also contains a filament 826 lighted from a source 827 controlled by a rheostat 828. Spirally wound around the filament, but out of contact therewith, is a grid electrode 830, and in a tubular extension of the bulb is a plate electrode 831. Surrounding or within the neck of the bulb is an auxiliary electrode 835. A source of direct current of relatively high voltage 836 is arranged in series with a choke coil 837 and the plate electrode 831 at one end and with the filament 826 at the other end. A battery 839 is located between the grid electrode 830 and one leg of the filament electrode 826. This source of direct current 838 is regulated by means of a suitable potentiometer. An iron core transformer 840 has a secondary coil 841 in the grid filament circuit and has a primary coil 842 which takes the place of the coil 109 of Fig. 2 and which connects the outer ends of conductors 110 and 111 of Fig. 2. Suitable lenses 845 and 846 of Fig. 20 take the place of lenses 108 of Fig. 2 and receive the light emitted from the end of the neck of the bulb 825 and direct the same in the form of a small beam or pencil upon the vibrating mirror 115 of Fig. 2 by which it is reflected to the vibrating mirror 116 and then to illuminate a spiral path upon the screen 86, as described in connection with Fig. 2. The construction and operation of this system shown in Fig. 20 are such that the intensity of the light emitted by the bulb 825 and directed by the lenses 845, 846 upon the reflector 115 at any particular moment depends directly upon the amount of current flowing through the coil 842 at that particular moment and consequently the beam of light reflected upon the screen 86 will produce an image of the object 14 of the sending system.

In Fig. 21 is shown diagrammatically a system which might be popularly characterized as a system for "seeing in the dark." This system produces from a distant object of low visibility an image which is clearly visible, and in one of its forms includes a light tight casing 850 provided at one end with an opening 851 for the admission of light rays from the distant object, which in Fig. 21 is shown as a ship 852.

To permit the casing 850 to be moved conveniently so as to direct its opening towards the distant object 852 the casing is mounted upon a fixed base 855 to rotate with respect thereto about a fixed vertical axis and also to oscillate with respect thereto about a horizontal axis intersecting the vertical axis and is arranged to be held fixed

in any position of adjustment about said axes by set screws 856 and 857.

Within the casing 850 is arranged a sending system for television constructed as in Fig. 1 modified as in Fig. 11, and having its light reflector 31 arranged to receive a light beam from the distant object 852 through the opening 851. In this form the lamp 200 and reflector 201 of Fig. 11 would be omitted from the casing 850 of Fig. 21 but obviously might be placed outside of the casing 850 to increase its visibility if this should be found desirable, but it is not considered that this would be either necessary or desirable in most cases providing a highly sensitive photo-electric cell 62 is utilized in the system within the casing 850. The sending system in casing 850 is connected by conductors 860 and 861 to any suitable receiving system 858, such, for instance, as the one shown in Fig. 2 whereby a clearly visible image of the distant object 852 will be produced.

It is to be understood that preferably the transmission system of Fig. 1 and the object 14 should be arranged in a dark room having dull black light absorbent inner walls; and this is true also of the receiving system of Fig. 2 with its screen 86. The transmission system and the receiving system of Fig. 8, the receiving system of Fig. 12, and the receiving system of Fig. 15^B should also be placed in dark rooms.

Although only a few of the various forms in which this invention may be embodied have been shown herein, it is to be understood that the invention is not limited to any specific construction but might be embodied in various forms without departing from the spirit of the invention or the scope of the appended claims.

Having described my invention, what I claim is:

1. The method of television which consists in illuminating successive points in a predetermined path on an opaque object, receiving the light rays made up of various color components from said path, chromatically disintegrating said rays and forming therefrom a series of impulses of light corresponding respectively in color to said components respectively, producing an electric current and modifying the same in accordance with said light impulses to produce current impulses.

2. The method of television which consists in illuminating successive points in a predetermined path on an opaque object, receiving the light rays made up of various color components from said path, chromatically disintegrating said rays and forming therefrom a series of impulses of light corresponding respectively in color to said components respectively, producing an electric current and modifying the same in accord-

- ance with said light impulses to produce current impulses, producing impulses of light in synchronism with and corresponding respectively in color with said first mentioned impulses of light and modifying said second mentioned impulses of light as a result of the action of said current impulses and causing said second mentioned impulses of light to illuminate successively successive 5 points in a predetermined path to produce an image of said object in its natural colors.
3. A system of television comprising a transmission system including means for producing a beam of light, means for vibrating said beam including a plurality of vibratory reflectors, a corresponding plurality of galvanometers provided with a plurality of vibratory coils respectively arranged to actuate said vibratory reflectors, an electric 10 circuit including said coils in series, means for producing in said circuit electrical oscillations of a given frequency modulated periodically in amplitude at a different frequency, in combination with a receiving system including means for producing a beam of light, and vibratory means controlled by said oscillations thus modulated for vibrating said last mentioned beam.
4. A light vibratory system including 15 means for producing a beam of light, a galvanometer having a coil arranged to vibrate about a given axis, a reflecting element arranged to receive said beam and to be vibrated about said axis by and in accordance with the vibration of said coil, a second galvanometer provided with a coil arranged to vibrate about an axis perpendicular to said first mentioned axis, a reflecting element arranged to be vibrated about said second mentioned axis by and in accordance with said second mentioned coil and to receive said beam reflected from said first mentioned element, an electric circuit including said coils in series, and means for producing 20 periodical electrical variations in said circuit to vibrate said coils.
5. A light vibratory system including 25 means for producing a beam of light, a galvanometer having a coil arranged to vibrate about a given axis, a reflecting element arranged to receive said beam and to be vibrated about said axis by and in accordance with said coil, a second galvanometer provided with a coil arranged to vibrate about an axis perpendicular to said first mentioned axis, a reflecting element arranged to be vibrated about said second mentioned axis by and in accordance with said second mentioned coil and to receive said beam reflected from said first mentioned element, an electric circuit including said coils in series and means for producing 30 periodical electrical oscillations of a given frequency periodically varied in amplitude at a different frequency, one of said coils hav-

ing a natural frequency of vibration slightly above the frequency of said variations, and the other of said coils having a natural frequency vibration slightly below the frequency of said variations, whereby said reflecting elements will be vibrated at the same frequency as the frequency of said variations but with a difference in phase between said elements.

6. A system of television including color 75 disintegrating means arranged to receive light from an object and to produce therefrom a plurality of series of light impulses, means controlled by said plurality of series respectively for producing a plurality of 80 series of electrical impulses of different frequencies respectively, and receiving means including means for producing two beams of light and color disintegrating means acting upon said beams and producing therefrom two series of light impulses of cyclically varying colors.

7. A system of television including a plurality of cooperating vibratory light reflectors, and means for vibrating the same comprising an electric circuit including a corresponding plurality of mechanically vibratory elements controlling said light reflectors respectively, and means for producing electrical impulses of a given frequency in 95 said circuit to vibrate said vibratory elements, said vibratory elements being tuned to natural frequencies of vibration different from said given frequency.

8. A system of television including a magnet, a coil arranged to vibrate between the poles of said magnet, a light reflector arranged to be vibrated by said coil about a given axis, a second magnet, a second coil arranged to vibrate between the poles of said second magnet, a light reflector arranged to be vibrated by said second coil about a second axis and to receive light from said first mentioned reflector, an electric circuit including said coils, means for producing in said circuit electrical oscillations having a predetermined frequency, said coils tuned to have natural frequencies of vibration respectively above and below said first mentioned frequency, and a receiving system having light vibratory elements vibrated in synchronism with said first mentioned vibratory elements as a result of the action of said oscillations.

9. In a system of television, means for producing a beam of light, means including a plurality of cooperating vibratory reflectors, for causing said beam to illuminate successively successive portions of a predetermined path on an object, and a plurality of cooperating reflectors synchronized in movement with said first mentioned reflectors and arranged to receive light reflected from said points and to direct the same over a given path.

10. In a system of television, means for producing a beam of light, means including a plurality of cooperating vibratory reflectors, for causing said beam to illuminate successively successive portions of a predetermined path on an object, and a plurality of cooperating reflectors synchronized in movement with said first mentioned reflectors and arranged to receive light reflected from said points and to direct the same over a substantially fixed path. 10
11. A system of television comprising means for producing an image of an object in the natural colors of the object as viewed from a given point and simultaneously producing a second image of said object in the natural colors of the object as viewed from a different point, said images being arranged to overlap and to be visible to the naked eye of an observer as a single image of said object in the natural colors of said object. 15
12. A system of television including means for illuminating successively the various points upon an opaque object in a predetermined path, means for receiving a beam of light reflected from the various points in the said predetermined path, color disintegrating means arranged to act upon said beam to produce therefrom successive impulses of differently colored light, means controlled by said impulses for producing electrical impulses varied in accordance with said light impulses, means for amplifying said electrical impulses, and receiving means comprising means for producing a beam of light, means for changing said beam into impulses of differently colored light, and means for causing said impulses to illuminate a path corresponding to said first mentioned path and synchronized therewith. 20
13. A transmission system for television including means for producing a beam of light, vibratory reflecting means for causing said beam to illuminate successively successive points lying in a predetermined path on an object, and vibratory reflecting means synchronized in movement with said first mentioned vibratory reflecting means for receiving light reflected from said points in succession and operative to direct the same along a fixed path. 25
14. A transmission system for television including means for producing a beam of light, means including a plurality of cooperating vibratory reflectors for causing said beam to illuminate successively successive points lying in a predetermined path on an object, and means including a plurality of cooperating vibratory reflectors synchronized respectively with said first mentioned reflectors for receiving light successively from said successive points and directing the same along a fixed path. 30
15. A receiving system for television in- cluding means for producing two beams of light, color disintegrating means for modifying said two beams to produce two series of light impulses, each series being cyclically varied in color, and means for causing said two series of colored impulses to cooperate in producing an image of an object in the natural colors of the same. 35
16. A receiving system for television including means for producing two beams of light, color disintegrating means for modifying said two beams to produce two series of light impulses, each series being cyclically varied in color, means for causing said two series of colored impulses to cooperate in producing an image of an object in the natural colors of the same, and auxiliary color disintegrating means through which said image may be viewed to give said image a stereoscopic effect. 40
17. A transmission system for television including color disintegrating means arranged to receive light rays from an object and operative to convert said light rays into a plurality of series of light impulses each of cyclically varying colors, and means controlled by said plurality of series of light impulses for producing a corresponding plurality of series of electrical impulses of different frequencies respectively. 45
18. Receiving means for television includ- ing means for producing a plurality of beams of light, color disintegrating means for modifying said beams to produce a plurality of series of light impulses, each series being cyclically varied in color, means controlled from a distance for determining the intensity of each of said series of impulses, and directional means for cyclically varying said plurality of series of colored im- pulses to cause the same to illuminate suc- 50
- cessive points in a predetermined path and thereby produce an image of an object in the natural colors of the object. 55
19. Receiving means for television includ- ing means for producing a plurality of beams of light, color disintegrating means for modifying said beams to produce a plurality of series of light impulses, each series being cyclically varied in color, means for cycli- 60
- ally varying said plurality of series of col- ored impulses to cause the same to illuminate successive points in a path and thereby pro- 65
- duce an image of an object in the natural colors of the object, and color disintegrating means through which said image may be viewed to produce a stereoscopic effect. 70
20. A stereoscopic system comprising means for producing two beams of white light, color disintegrating means for transforming said two beams into two series of light impulses, the impulses of each series differing in color, means for causing said two series of impulses to cooperate in producing 75

two apparently over-lapping images of an object in the natural colors of the object and means for permitting an observer to view one of said images exclusively through one eye while viewing the other of said images exclusively through the other eye thereby receiving a stereoscopic effect.

21. A stereoscopic system comprising means including a rotary color disintegrator for producing in rapid alternation two apparently over-lapping images of an object in the natural colors of the object, as viewed from two different points respectively, and means including a rotary color disintegrator synchronized with respect to said first mentioned disintegrator for viewing one of said images exclusively through one eye while viewing the other of said images exclusively through the other eye.

22. A system of light control comprising means for producing a beam of light, movable light reflecting means arranged to vary the direction of movement of said beam and movable means synchronized in movement

with said reflecting means for varying the intensity of said beam.

23. A system of light control comprising means for producing a beam of light, movable light reflecting means arranged to vary the direction of movement of said beam and movable means synchronized in movement with said reflecting means for varying the intensity of said beam, in accordance with the rate of variation in the direction of movement of said beam.

24. The method of stereoscopic projection in natural colors which comprises, projecting on a screen two overlapping images in complementary colors as viewed from separate points, rapidly and cyclically varying the color by each of said overlapping images and viewing said images by means of a color screen which correspondingly cyclically varies the color passed with respect to each of the observer's eyes.

This application signed this 9th day of Aug., 1923.
